UNITED STATES PATENT OFFICE

134,864

DESIGN FOR A BROOCH OR SIMILAR ARTICLE

Wallace A. Perrett, Rockford, Ill.

Application March 23, 1942, Serial No. 106,288

Term of patent 3½ years

To all whom it may concern:

Be it known that I, Wallace A. Perrett, a citizen of the United States, residing at Rockford, in the county of Winnebago and State of Illinois, have invented a new, original, and ornamental Design for a Brooch or Similar Article, of which the following is a specification, reference being had to the accompanying drawing, forming part thereof wherein the figures are wholly fanciful.

In the drawing:

I claim:

The ornamental design for a brooch or similar article, substantially as shown and described.

WALLACE A. PERRETT.
